UNITED STATES PATENT OFFICE.

WILLIAM SPENCER, OF PHILADELPHIA, PENNSYLVANIA.

WATER-HEATER.

1,149,301.

Specification of Letters Patent.

Patented Aug. 10, 1915.

Application filed August 31, 1914. Serial No. 859,453.

To all whom it may concern:

Be it known that I, WILLIAM SPENCER, a citizen of the United States, residing at Philadelphia, in the county of Philadelphia and State of Pennsylvania, have invented certain new and useful Improvements in Water-Heaters, of which the following is a specification.

This invention relates to the subject of water heaters of the so-called "instantaneous" type, and has particular reference to a novel device of this character constructed especially for rapidly heating running water to a high temperature.

The primary object of the invention is to provide a practical device of the character indicated that will freely expose the water to a maximum heating surface to insure the instantaneous heating thereof by means of a gas or oil flame. Many devices of this character employ a "heating-coil," but this method does not present, as a rule, an adequate heating surface to the flame, because the bottom coil only receives the direct heat of the flame. Accordingly, the present invention contemplates passing the water in a zigzag course through a plurality of water tubes of comparatively small diameter which are in direct contact with the flame, and then passing it through an incasing water-jacket of extended area and restricted thickness, and which jacket is so combined with the water tubes as to form a housing-hood therefor.

Another object of the invention is to provide a novel, simple and substantial construction which may be easily and economically manufactured, and which will be not only of special utility in household heating systems, but at the same time may be used to advantage for the generation of steam.

With the above and other objects in view which will more readily appear as the nature of the invention is better understood, the same consists in the novel construction, combination and arrangement of parts hereinafter more fully described, illustrated and claimed.

A preferred and practical embodiment of the invention is illustrated in the accompanying drawings in which—

Figure 1 is a transverse sectional view of one form of the invention arranged within a suitable casing. Fig. 2 is a bottom plane view of the heating unit without the casing.

Fig. 3 is a vertical sectional view of a modification of the invention.

Similar reference characters designate corresponding parts throughout the several figures of the drawings.

Referring to the details of construction shown in the several figures of the drawings, the numeral 1 designates a suitable casing having supported therein upon the blocks 2 or other suitable supporting means, a heating unit designated in its entirety by the numeral 3. Directly beneath the said heating unit 3 there is supported a suitable burner 4 which in the present instance is shown to be a gas burner, though it will of course be understood that any other desired type of burner may be used with equal facility.

The form of the invention disclosed in Figs. 1 and 2 essentially comprises oppositely arranged water headers 5 and 6 which for the sake of convenience may be respectively termed a receiving header and transferring header. These headers are connected by a plurality of water tubes 7 which are preferably of comparatively small diameter and exposed to direct contact with the flame from the burner 4. The receiving header 5 is provided at one end with a water inlet connection 8, while the opposite or transferring header 6 is in communication through a suitable port 9 with a flat water-jacket 10 of restricted bore and extended area. That is to say, the water jacket 10 is preferably very thin, and arranged directly above the bank of water tubes 7 forming a housing-hood therefor so that heat is directed thereagainst at the same time that it is directed against the tubes 7. This jacket is co-extensive with the width and length of the bank of water tubes and headers, and at its end opposite the location of the port 9 is provided with a tapered or convergent outlet portion 11 having at its apex an outlet nipple 12 to lead the water to the distributing piping.

From the foregoing description of one type of the invention, it will be apparent that water entering the receiving header 5 through the inlet connection 8 will be forced through the bank of tubes 7 which are highly heated by the flame from the burner 4 into the header 6 from whence it is transferred to the water jacket 10 and retraces its course back over the flame toward the

convergent outlet portion 11 from which it makes its exit through the outlet nipple 12 to a faucet or some portion of the plumbing system.

5 The modification of the invention shown in Fig. 3 provides a more extensive heating surface for the water than does the other type of the invention. This form, like the other, essentially comprises oppositely arranged 10 water headers 13 and 14, the former being the receiving header and the latter the transferring header. With particular reference to the receiving header 13, it will be observed that the same is provided with a 15 central partition 15 which divides the same into a receiving compartment 16 and a delivery compartment 17, the former communicating with the water supply by means of a pipe connection 18. The compartment 20 16 which extends the entire length of the header, and receives water from the source of supply communicates with the transferring header 14 by means of a plurality of arched water tubes 19, thus conducting the 25 cold water directly over the flame from a burner 4^a and discharging the same into the chamber 20 of the header 14. For the purpose of retarding passage of the water so that it will get the full benefit of the heat 30 when passing through the tubes 19, the said chamber 20 is provided with oppositely arranged baffles 21 which terminate short of each other and provide a contracted passageway 22 opening in the discharge chamber 35 23. From the discharge chamber 23, water is conducted back to the header 13 by means of a plurality of tubes 24, though upon its return to the header 13, the water is 40 discharged into the delivery compartment 17 from whence it makes its way through the port 25 to a water jacket 26 which covers both banks of tubes 19 and 24 and terminates on the opposite side of the device at the lower portion of the transferring header 45 14. At this point, the water jacket 26 is provided with an outlet nipple 27 which corresponds to the nipple 12 in the other form of the invention.

From the foregoing description of the 50 modified form of the invention, it will be apparent that the water retraces its course over the flame from the burner 4^a three times, twice through a plurality of thin water tubes, and in the end through a water 55 jacket of restricted thickness which is co-extensive with the headers and tubes, and which is capable of absorbing substantially all of the heat not absorbed by the banks of

tubes 19 and 24, thereby forming an extremely efficient heater.

It is thought from the explanation of the structural features of the several forms of the invention that the many features and advantages of the same are readily apparent, and it will of course be understood that minor details of construction may be changed without departing from the spirit or sacrificing any of the advantages of the invention.

I claim:

1. A water heater of the class described, including oppositely disposed water headers arranged in parallel relation, one of said headers having a water inlet connection, a water jacket of extended area and restricted bore arranged on and supported by both of said water headers and in communication with one of the same, a heater device located beneath said water jacket, and a plurality of closely spaced water tubes establishing communication between said headers and arranged in close proximity to said jacket which forms a hood therefor.

2. A water heater including a receiving header having separate receiving and delivery compartments, a water transferring header, a plurality of tubes connecting the receiving compartment with the interior of the transferring header, a plurality of tubes connecting the transferring water header with the delivery compartment of the receiving header and a flat water jacket of extended area and restricted thickness in communication with the delivery compartment and having an outlet connection.

3. A water heater including a receiving header having separate receiving and delivery compartments, a water transferring header, a plurality of arched tubes connecting the said receiving compartment with the transferring header, a plurality of arched tubes arranged at one side of the tubes connecting the receiving compartment with the transferring header, said latter tubes connecting the transferring header with the said delivery compartment of the receiving header, and a water jacket arranged over and about said tubes and in communication with the delivery compartment of the receiving header.

In testimony whereof I hereunto affix my signature in the presence of two witnesses.

WILLIAM SPENCER.
